[57] CLAIM

The ornamental design for a retainer for securing electrical plugs to an outlet, as shown.

DESCRIPTION

FIG. 1 is a perspective view of a retainer for securing electrical plugs to an outlet showing my new design, on an enlarged scale;

FIG. 2 is a front elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a rear elevational view thereof.
